FIRE EXTINGUISHER

Charles R. D'Olive, Dayton, Ohio, assignor to
The Fyr-Fyter Company, Dayton, Ohio, a cor-
poration of Ohio

Application June 17, 1929. Serial No. 371,408

17 Claims. (Cl. 169—32)

This invention relates to fire extinguishers, and particularly to fire extinguishers of the chemical reaction type.

One of the principal objects of this invention is to provide a fire extinguisher mechanism of this type which is simple and sturdy in construction, has long life, is capable of receiving a charge of highly reactive chemicals and provides for a controlled limiting of the rate of discharge and mixing of the chemicals upon use of the mechanism, and is constructed to insure reliability and effectiveness in operation.

Other objects and advantages of this invention will be apparent from the following description, the accompanying drawing and appended claims.

In the drawing, in which like characters of reference designate like parts throughout the several views thereof—

Fig. 1 is a central vertical sectional view of an extinguisher constructed in accordance with this invention;

Fig. 2 is a horizontal sectional view taken on the plane of the line 2—2 of Fig. 1; and

Fig. 3 is an enlarged partial vertical sectional view illustrating the position of parts in inverted position of the extinguisher.

While the fire extinguisher herein described will satisfactorily operate upon a variety of charge materials, it is adapted particularly to receive a highly reactive charge comprising a relatively concentrated carbonate solution such as potassium carbonate within the outer container, and an acid such as chlorosulphonic acid within the inner container. The present extinguisher is constructed to effect such a controlled limiting of the rate of discharge of acid and mixing of the chemicals upon inversion of the extinguisher as to cause the pressure to rise slowly and to be maintained throughout a greater portion of the period of discharge, as is required by underwriters' laboratories. The extinguisher is constructed to be highly reliable and fool-proof in operation.

Referring to the drawing, the extinguisher comprises a sheet metal container 10, preferably of sheet copper tinned on the inside, having a portion 11 with a beaded edge 12 which serves as a base on which the container may set when in upright position. The lower end of the container is closed by a sheet metal bottom 13 which may be fastened to the wall of the outer shell in any suitable manner such as by soldering. The top of the shell is provided with a centrally arranged opening which receives therein a cover casting 14, preferably copper, to which this end of the shell

is soldered. The upper end of the cover casting 14 is threaded to receive thereon a cover member 15 carrying a suitable handle 16, which as shown is in the form of a ring to serve as a base upon which the extinguisher is adapted to rest when inverted.

Adjacent the upper end of the extinguisher, and passing through the wall of the extinguisher shell is a discharge casting 20. This casting is provided with an enlarged shoulder 21 which is soldered to the shell. Attached as by soldering to the inner end of the casting 20 is a flaring sheet metal member 22 receiving a screen 23, and the outer end of the casting is provided with a threaded nipple 24 which receives the usual flexible hose 70 carrying a discharge nozzle 26.

When an acid such as chlorosulphonic acid is used, it is preferable to provide a hermetically sealed acid container to prevent fuming and corrosion. In order to insure proper operation of the extinguisher upon inversion when such a sealed acid container is used, the inner container is provided with a frangible closure, and means are provided for positively breaking the frangible closure upon inversion. As shown, the upper end 75 of the inner face of the cover casting 14 is offset to provide a shoulder 30 upon which an annular ring or supporting member 31 rests. The member 31 is preferably a metal casting and has a downwardly depending portion 32 and an inwardly extending annular ring portion 33. Connected to the portion 33 as by soldering is a sheet metal tube 35. The tube is closed at its lower end by a base casting 36 preferably formed with a circular groove 37 within which the lower end 80 of the tube 35 is soldered. The upper end of the tube 35 and the space 38 above the annular ring member 33 is in communication with the space within the outer container through a series of ports 39 formed through the annular ring member, the tube thus opening above the normal liquid level within the outer container 10.

Resting within the tube 35 is a hermetically sealed acid bottle 40. Slidably mounted within an upstanding boss 42 of the cover 15 is a breaking plunger 43. This plunger comprises an outer part indicated at 44 having at its inner end which extends through the cover 15 to the interior of the extinguisher an inner threaded bore shown in Fig. 1 and indicated at 46. Within the extinguisher is a second inner plunger part 47 having an upper exteriorly threaded end of smaller diameter 48 which is detachably received within the bore 46. The part 44 has at its inner end an exteriorly screw threaded portion 49 110

of smaller diameter than the upper portion of the part 44 to thereby form a shoulder 50. The threaded end 49 passes through a circular opening in a sealing flexible diaphragm 52 which is firmly clamped at its periphery between the upper surface of the cover casting 14 and the lower surface of the cover 15. This diaphragm may be formed of any suitable flexible material which is adapted to yield to permit movement of the plunger 43, rubber being very satisfactory for this purpose. In order to clamp the diaphragm 52 firmly to the plunger 43, a metal washer 54 is positioned above the diaphragm 52 and about the threaded end 49, the washer being of such size as to contact with the shoulder 50. Threaded on the inner end of the threaded portion 49 and on the opposite side of the diaphragm 52 from the washer 54 is a threaded nut or thumb 56. The upper end of the plunger 43 carries a cover cap 57 fastened thereto in any suitable manner as by a rivet 58, and a spring 59 is interposed between the cap 57 and the top of the boss 42 to normally urge the plunger and sealing diaphragm to its upper position tight against the cover 15 to thereby prevent leakage.

The construction of the cover and plunger parts is such that the plunger may be completely assembled upon the cover before the cover is mounted upon the extinguisher. With the cover 15 removed, the outer portion 44 of the plunger 43, to which the spring 59 and cap 57 have been previously attached, is inserted through the opening in the boss 42. The washer 54 is then mounted in place upon the exposed threaded end 49 beneath the cover 15, and the diaphragm 52 is then positioned over this end and the washer and diaphragm are firmly clamped in position on the plunger against the shoulder 50 by screwing on the thumb screw 56. The inner part of 47 of the plunger is then screwed into place within the bore 46. The cover is then ready to be mounted in place upon the extinguisher, and as the cover 15 is screwed down upon the exterior threads of the casting 14 the outer periphery of the diaphragm 52 is firmly clamped in sealing relation between the top surface of the casting 14 and the bottom of the cover 15.

It is found, when using a charge comprising a solution containing per unit volume large quantities of carbonate and an acid such as chlorosulphonic acid, that the initial reaction of the chemicals is very violent, and the gas pressure tends to build up too rapidly when the conventional extinguisher constructions are used. In accordance with this invention, the parts are so constructed that the plunger 43 first functions to break the frangible closure of the acid bottle 40, and then serves to effect a controlled limiting of the rate of discharge of acid from the container. This is accomplished by providing the inner container 40 with a metering orifice of predetermined size into which the lower part 47 of the plunger 43 is adapted to project when the parts are in feeding position, the size of the plunger being coordinated with the size of the metering orifice to materially restrict the opening resulting from the breaking of the frangible closure of the container.

The construction of the acid bottle 40 is more clearly illustrated in Fig. 3. As shown, the bottle may be an ordinary thick walled glass bottle 65 having an upper exteriorly threaded neck portion 66 with a filling opening through which the acid charge is introduced into the bottle. Mounted over this filling opening on the neck of the bottle

is a thin frangible disk 67, such as a glass disk. This disk is firmly clamped in place between asbestos washers 68 and 69 by a metal cap member 70 which is threaded upon the neck 66. Positioned over these parts is a metal metering member 72, which as shown may be formed as a metal stamping having a depending skirt portion 73 which surrounds the bottle neck. The upper portion of the stamping is inturned and downwardly inclined as indicated at 74, and the lower end of the inturned portion preferably rests upon the top of the bottle. This inturned portion forms a circular orifice 75 of predetermined restricted size which is positioned directly in alignment with the frangible disk 67 therebeneath. The cap member 70 is also provided with a circular opening 77, so that the frangible disk 67 is directly exposed when the parts are in place through the orifice 75 and the opening 77. The stamping 72 is preferably fastened to the bottle by means of a plastic cement indicated at 78, such as a mixture of sodium silicate and china clay, plaster of Paris, or a mixture of litharge and glycerine. A cement composed of a mixture of sodium silicate and china clay is preferred for this purpose as it remains plastic for longer periods, is easier to handle and is quite resistant to acid.

In preparing the charge holding container or bottle 40 with acid charge therein, the acid is first poured in through the open mouth of the bottle, and then the washer 68, disk 67 and washer 69 are positioned in order within the cap 70 which is screwed down tight upon the threaded bottle neck to hermetically seal the bottle. A quantity of plastic cement is then placed about the bottle neck, or within the depending skirt 73 of the metal stamping, or both, and the neck of the bottle inserted within the skirt until the lower surface of the inturned portion 74 contacts with the top of the bottle. The excess cement is scraped off, and the bottle laid aside to permit the cement to set to firmly attach the metering member over the frangible closure of the bottle. The bottle neck is preferably formed with an irregular surface such as a rib 79, which serves to provide a better cementing connection.

In operation, the container 10 is inverted and bumped down upon the floor or other convenient surface to drive the plunger 43 inwardly. The length of the plunger 43 on the exterior of the cover is such that the upper surface of the cap 57 protrudes a short distance above the top of the handle 16. When the extinguisher is thus bumped down upon the floor, the cap 57 and plunger 43 are moved inwardly until the handle 16 contacts with the floor, which serves to limit the inward driving movement of the plunger. Should the plunger be driven inwardly by hand before the extinguisher is inverted, the lower surface 80 of the cap 57 is adapted to contact with the top of the cover 15 to limit the movement of the plunger. The inner end of the part 47 of the plunger is provided with a breaking projection adapted to shatter the frangible disk 67 so that enough of the glass of the disk is removed to provide an opening which is larger in extent than the opening of the orifice 75. The opening in the bottle neck is also larger in cross-section than the orifice 75 so that this orifice then becomes the effective metering orifice. A very suitable form of breaking projection is that shown, which comprises a plurality of radially extending ribs 81, the lower surface of each of which is inclined downwardly as at 82 so that all the ribs meet in a breaking point 83. With such a con-

struction and with a thin frangible disk 67, it is found that the impact of the extinguisher upon the floor is sufficient to completely shatter the disk 67 in the manner described, so that the disk 67 shears off adjacent its area of support on the rim of the bottle neck 66 as shown in Fig. 3.

After the extinguisher is inverted and the frangible closure 67 broken, the bottle 40 being movably mounted within the tube 35 slides down this tube about the plunger part 47 to the feeding position illustrated in Fig. 3. The bottle is preferably provided with outwardly extending ribs 85 to insure a positive sliding movement, as well as to guide the descent of the bottle so that the point 83 of the plunger enters the large opening formed by the inclined surface 74 which guides the point into and through the orifice 75 of the metering member. As soon as acid is discharged from the bottle 40 and mixes with the carbonate solution, the gas pressure developed coupled with the tension in the spring 59 forces the plunger and sealing diaphragm 52 back into sealing engagement with the cover 15 to prevent gas leakage. This construction eliminates the necessity of a packing box for the plunger and provides a freely operable construction which will not stick after long periods of non-use. The bottle 40 slides down about the plunger 43 in its retracted position until the metering member 72 comes into engagement with the projections 86 formed on the nut 56. As shown, the ordinary diametrically opposed projections of the thumb screw which permit easy manual operation may be used to limit the downward movement of the bottle 40. The acid discharges at a limited rate through the restricted annular channel 87 formed between the outer surface of the plunger part 47 and the periphery of the orifice 75, and thence through the space between the projections 86 of the thumb screw into the chamber 38.

When the extinguisher is inverted, the liquid within the outer container rushes downwardly and into the annular channel 90 formed between a tubular sheet metal member 91 carried by the supporting member 31 and the outer surface of the tube 35. The tubular member 91 is of a size to surround the upper end of the tube 35 in such spaced relation as to provide a restricted channel 90, which cooperates with the restricted ports 39, to effect controlled limiting of the rate of mixing of the chemicals. With this construction, the expelling gas pressure rises at a controlled rate, and effective gas pressure is maintained throughout a greater portion of the period of discharge.

When it is desired to supply a fresh charge to the extinguisher, the cover 15 and attached parts including the plunger 43 and diaphragm 52 are removed by unscrewing the cover. The supporting member 31 may then be readily lifted out of the outer casing 10 to remove the tube 35 and inner container 40. The inner container may be reused if desired by removing the metal stamping member and cap 70 and replacing these with new parts, or a new acid bottle assembly may be provided. The basic charge is supplied to the outer container 10, and then the supporting member 31 with acid bottle 40 in place within the tube 35 is inserted within the neck of the extinguisher until the supporting member contacts with the shoulder 30. The cover 15 is then replaced and the extinguisher is ready for further use.

While the form of apparatus herein described constitutes a preferred embodiment of the invention, it is to be understood that the invention

is not limited to this precise form of apparatus, and that changes may be made therein without departing from the scope of the invention which is defined in the appended claims.

What is claimed is:

1. In a fire extinguisher of the character described, an outer container having a bore, a breaking plunger including a rod slidably mounted in said bore of the container and extending to the exterior thereof, a cap for the rod on the exterior of the outer container, said rod having within the container and exterior screw-threaded portion and a shoulder formed thereon at the outer end of the screw-threaded portion, a flexible sealing diaphragm mounted for sealing the bore receiving said plunger rod mounted within said container and having its outer portion fixed relative to said container, receiving therethrough the screw-threaded portion of said rod, a washer positioned between said diaphragm and said shoulder and adapted to bear against the interior of said container, a second washer on the opposite side of said diaphragm from said first washer threaded on said screw-threaded portion and clamping said diaphragm firmly between said washers and against said shoulder, and resilient means acting between said container and said cap and rod for normally holding said first mentioned washer in engagement with the interior of said container, so that the said washer extends across from the interior of the container to the shoulder on the rod and effectively closes the said bore receiving the rod, the construction being such that when said plunger is held in its normal inoperative position the said flexible sealing diaphragm is disposed in a substantially flat and untensioned position.

2. In a fire extinguisher of the character described, an outer container having a bore, a breaking plunger including a rod slidably mounted in the bore in said container and extending to the exterior thereof, a cap for the rod on the exterior of said outer container, said rod including an outer part extending through said container and having a screw-threaded bore in the inner end thereof, and an inner detachable part having a screw-threaded end received within said bore, said outer part having an exterior shoulder adjacent its inner end and exterior screw threads on the inner side of said shoulder, a flexible sealing diaphragm mounted for sealing the bore receiving said plunger rod within said container and having its outer portion fixed relative to said container, said diaphragm receiving therethrough the exteriorly threaded end of said outer plunger part, a washer positioned within the container about said plunger between said diaphragm and said shoulder and adapted to bear against the interior of said container, a clamping nut on the opposite side of said diaphragm threaded on said exterior screw threads and clamping said diaphragm firmly between said washer and nut and against said shoulder, and resilient means acting between said container and said rod for normally holding said first mentioned washer in engagement with the interior of said container, so that the said washer extends across from the interior of the container to the shoulder on the rod and effectively closes the said bore receiving the rod, the construction being such that when said

plunger is held in its normal inoperative position the said flexible sealing diaphragm is disposed in a substantially flat and untensioned position.

3. In a fire extinguisher of the character described, a container having a filling opening and

- adapted to hold a quantity of liquid, a frangible disk closure for said filling opening, and cover means serving to clamp said frangible disk closure in place to hermetically seal said container, 5 said cover means having an orifice of predetermined restricted size through which the liquid within the container is adapted to discharge after breaking of said frangible disk closure to effect a controlled limiting of the rate of discharge of 10 liquid from the container.
4. In a fire extinguisher of the character described, a container adapted to hold a quantity of liquid, a frangible disk closure for said container, a member for fastening said disk in place 15 on the container to hermetically seal the container, and a metering member overlying said first mentioned member and attached to said container, said metering member having an orifice of predetermined size through which the 20 liquid within said container is adapted to discharge after breaking of said frangible disk closure.
5. In a fire extinguisher of the character described, an acid bottle adapted to contain an acid 25 and having a threaded neck portion, a frangible disk closure for said neck portion, a screw cap for holding said closure in place to hermetically seal said bottle, and a metering member overlying said screw cap and attached to said bottle, said metering member having an orifice of predetermined size through which the liquid within 30 said container is adapted to discharge after breaking of said frangible closure.
6. In a fire extinguisher of the character described, a container adapted to hold a quantity of liquid, a frangible disk closure for said container, a member for fastening said disk in place to hermetically seal said container, and a metering member overlying said first mentioned member and cemented to said container, said metering member having an orifice of predetermined size through which the liquid within said container is adapted to discharge after breaking of 40 said frangible disk.
7. In a fire extinguisher of the character described, an acid bottle adapted to contain an acid and having a threaded neck portion, a frangible disk closure for said neck portion, a screw cap threaded onto said neck portion to clamp 45 said disk in place to hermetically seal said bottle, a metal stamping having a depending skirt surrounding said neck portion and an inturned portion resting upon said bottle top and forming a metering orifice of predetermined size 50 above said frangible disk through which the acid within said bottle is adapted to discharge after breaking of said frangible disk, and a cement positioned between said metal stamping and said neck portion to attach the stamping to the 55 bottle.
8. In a fire extinguisher of the character described, a container adapted to hold a quantity of liquid, a frangible disk closure for said container, a cap member for clamping said frangible disk in place to hermetically seal said container, 60 said cap member having an opening on the outer side of said frangible disk, and a metering member overlying said cap member and attached to said container, said metering member having an orifice of predetermined restricted size through 65 which the liquid within said container is adapted to discharge after breaking of said frangible disk closure, said orifice being smaller than said opening in the cap member and smaller than the

effective opening of the container that results upon breaking of the frangible disk.

9. A fire extinguisher of the character described, comprising an outer container adapted to receive a liquid, a hermetically sealed frangible inner container adapted to hold a second liquid for reaction with said first mentioned liquid upon operation of the extinguisher, said inner container having a discharge orifice of predetermined restricted size, and a movably mounted 80 breaking plunger adapted to break said frangible container, said plunger and said inner container being so cooperatively arranged that the plunger is positioned within said orifice of the inner container during the period of liquid discharge 85 therefrom to effect a limiting of the rate of discharge of liquid therefrom.

10. A fire extinguisher of the character described, comprising an outer container adapted to receive a liquid, a hermetically sealed frangible inner container adapted to contain a second liquid for reaction with said first mentioned liquid, said inner container having a metering orifice through which the liquid therein is adapted to discharge after breaking of said frangible 90 container, and a movably mounted breaking plunger adapted to break said frangible container and then cooperate with said metering orifice to restrict the discharge of liquid therefrom, the size of the metering orifice being coordinated 95 with the size of the plunger to effect a controlled limiting of the rate of discharge of liquid from the inner container.

11. An invertible fire extinguisher of the character described, comprising an outer container adapted to receive a liquid, a hermetically sealed frangible inner container having a metering orifice and movably mounted therein and adapted to contain a second liquid for reaction with said first mentioned liquid, a movably 100 mounted breaking plunger adapted to break said frangible container for discharge of the liquid through said metering orifice, the construction being such that upon inversion of the extinguisher and after breaking of said inner container the latter then slides to feeding position about said plunger with the plunger entering within the said metering orifice to provide a restricted channel between the plunger and the wall of the orifice to effect controlled limiting of 105 the size of the plunger to effect a controlled limiting of the rate of discharge of liquid from the inner container.

12. A fire extinguisher of the character described, comprising an outer container adapted to receive a liquid, a hermetically sealed frangible inner container movably mounted therein and adapted to contain a second liquid for reaction with said first mentioned liquid upon inversion of the extinguisher, said container having a metering member with an orifice of predetermined size, a movably mounted breaking plunger operable from the exterior of said extinguisher and adapted to break said frangible container, the construction being such that upon inversion of the extinguisher and after breaking 115 of said frangible container the said container then slides to feeding position about said plunger with the plunger extending within the orifice of said metering member, and means for limiting the sliding movement of said inner container, 120 the size of the plunger being coordinated with the size of the said orifice of the metering member to effect a controlled limiting of the rate of discharge of liquid from the inner container.

13. A fire extinguisher of the character de- 125

- scribed, comprising an outer container adapted to receive a liquid, a hermetically sealed frangible inner container movably mounted therein and adapted to contain a second liquid for reaction with said first mentioned liquid, a breaking plunger movably mounted within the extinguisher and operable from the exterior to break said frangible container, said container then sliding to feeding position about said plunger on inversion, a sealing diaphragm within said outer container for said plunger, and means for fastening said diaphragm to said plunger, said means having a projection thereon for limiting the sliding movement of said inner container. 5 80
14. In a fire extinguisher of the character described, an outer container, a sealed inner container therein, a removable plunger slidably mounted in said outer container and extending to the exterior thereof, said plunger being adapted to 10 effect opening of said inner container, a flexible sealing diaphragm within said outer container having a portion connected to and movable with said plunger and another portion held in fixed position relative to said outer container, means 15 urging said plunger toward an inoperative position, and means carried by said outer container for limiting the said movement of the plunger, the construction being such that when said plunger is held in its normal inoperative position the 20 said flexible sealing diaphragm is disposed in a substantially flat and untensioned position. 25
15. In a fire extinguisher of the character described, an outer container, a hermetically sealed inner container movably mounted within said outer container, a movably mounted breaking plunger adapted to effect opening of said inner container, guiding means for said inner container arranged so that after movement of the plunger to open said inner container the inner 30 container then slides into feeding position about said plunger with the plunger entering the broken end of said inner container, means for limiting the movement of the plunger, and means for limiting the sliding movement of the inner container 35 whereby the inner container in feeding position is in fixed position relative to said plunger. 40
16. In a fire extinguisher of the character described, an outer container adapted to receive a liquid, a hermetically sealed inner container 45 movable mounted therein and adapted to contain a second liquid for reaction with said first men-
- tioned liquid upon inversion of the extinguisher, means for supporting said inner container in upright position of the extinguisher and for guiding said inner container in its movement upon inversion of the extinguisher, a breaking plunger movably mounted in said outer container in alignment with said inner container, means for normally maintaining said plunger in position with the breaking end thereof in spaced relation to said inner container, said means serving to return said plunger to said normal position after movement of the plunger to effect opening of said inner container, the construction being such that upon inversion of the extinguisher and after opening of the inner container by the plunger the said inner container then slides into feeding position about said plunger with the plunger positioned within the open portion of said inner container, and means for limiting the said sliding movement of said inner container, whereby the inner container in feeding position is in fixed position relative to said plunger. 50 85
17. In a fire extinguisher of the character described, an outer container adapted to receive a liquid, a hermetically sealed inner container movably mounted therein and adapted to contain a second liquid for reaction with said first mentioned liquid upon inversion of the extinguisher, a tube for supporting said inner container, the lower end of said tube being closed and the upper end being open and in communication with the space within said outer container, a breaking plunger movably mounted in said outer container in alignment with the open end of said tube and adapted to effect opening of said inner container, 100 means urging said plunger away from said inner container, means for limiting the said movement of the plunger, said inner container being supported within said tube adjacent the breaking end of the plunger, the construction being such that upon inversion of the extinguisher and after opening of the inner container by the plunger the said inner container then slides down said tube into feeding position about the plunger which has returned to normal retracted position, the plunger being then positioned within the open portion of said inner container, and means for limiting the said sliding movement of said inner container. 105 90 95
